UNITED STATES PATENT OFFICE.

FRANK NYE, RICHARD F. DENHAM, AND OLE KNUDSON, OF LAKE PARK,
IOWA.

HAND-HOLD FOR GUNS.

SPECIFICATION forming part of Letters Patent No. 445,192, dated January 27, 1891.

Application filed June 27, 1890. Serial No. 356,999. (No model.)

To all whom it may concern:

Be it known that we, FRANK NYE, RICHARD F. DENHAM, and OLE KNUDSON, citizens of the United States of America, and residents 5 of Lake Park, in the county of Dickinson and State of Iowa, have invented an Improved Hand-Hold for Guns, of which the following is a specification.

Our object is to provide a suitable hand-10 hold on the fore-end of a gunstock, which may be adjusted to suit the varying lengths of the arms of the users of the gun.

Our invention consists, first, in the construction of a handle consisting of an angular 15 bar having screw-threaded end portions, a wooden sleeve, a metal ferrule, and a nut; second, in the construction of interchangeable loops and clasps whereby the handle may be attached to different styles and sizes of 20 guns; third, in certain details of construction, as hereinafter set forth, pointed out in our claims, and illustrated by the accompanying drawings, in which—

Figure 1 is a transverse sectional view showing 25 the relative positions of the separate parts of our invention and the means employed to attach the device to the fore-end of a gun. Fig. 2 is a side view showing a section of a gun having the complete device attached thereto. 30 Fig. 3 is a transverse sectional view showing a modified form of the device attached to a double-barreled shotgun. Figs. 4, 5, 6, and 7 are modifications of the device. Fig. 8 is a face view of a device adapted to be fixed to 35 the wooden stock, as shown in Fig. 7.

A represents the body portion of a straight metal bar that is angular at its central portion and round and screw-threaded at its end portions B and B².

40 C represents a wooden sleeve having a longitudinal angular bore adapted to admit the bar A.

D represents a metal ferrule, one end of which is adapted to fit over the upper end of 45 the sleeve C, and the opposite end is concaved. This ferrule D has a circular bore in its central portion adapted to admit the end portion B of the bar A.

E represents an elongated circular nut 50 adapted to engage the end portion B² of the bar. This nut has an annular bead F, adapt-

ed to engage the end of the sleeve C and to project past the side of said ferrule, to be grasped by the fingers of the user, to be rotated thereby. The surface of said bead is 55 serrated.

H represents a screw-seat adapted to be fixed in a mortise in the lower side of the fore-end J of the wooden stock of a gun. The lower end of said screw-seat is convex to fit 60 the upper end of the ferrule D, and the upper end is concaved to fit the lower side of a gun-barrel.

K represents the barrel of a single-barreled gun. 65

In Fig. 3, L represents the barrels of a double-barreled gun.

M is a metal clasp consisting of two converging hooks adapted in size and shape to admit the fore-end J and barrels L. The free 70 end portions of the hooks are bent downward, so that the points thereof may enter the depression between the web N and the barrels L. This clasp M has a screw-seat formed integral on its lower end adapted in shape to fit to the 75 upper end of the ferrule D, and to admit the end B of the bar A.

O represents a modified form of clasp adapted for attaching the handle to Winchester repeating arms and single-barreled guns. 80

P represents a modified form of clasp adapted to attach the handle to the old styles of Spencer or Colt's repeating arms.

S represents a modified form of clasp adapted to attach the handle to the new styles 85 of Spencer or Colt's repeating arms.

In Fig. 7, T represents a cap-nut, an enlarged plan view of which is shown in Fig. 8. This nut is set in a mortise in the fore-end J and secured by means of a screw, and is 90 adapted to admit and form a bearing for the end portion B of the bar A.

In the practical use of our invention we insert the bar A into the wooden sleeve and screw the nut F on the end B² a short distance. 95 Then insert the end B through the ferrule D and screw it into the screw-seat H by rotating the sleeve C as far as desired, and then screw up the nut F until it is tight.

In using the modified forms of clasps we 100 attach the handle in the same way, and to adjust it to suit the varying lengths of arms of

various users we loosen the clasp by a backward rotary movement of the sleeve C and slide the clasp along the gun in the direction desired to the suitable position, and then 5 tighten the clasp in the usual way. The complete invention may be thus interchangeably used on the different forms of guns named.

Having thus described our invention, what we claim as new, and desire to secure by Letters Patent, is—

- 15 1. A hand-hold for guns, composed of a bar having an angular body portion and round screw-threaded end portions, an outer sleeve or handle having a longitudinal angular bore, an adjusting-nut on one end portion of the rod, and a metal ferrule on the opposite end portion of the bar, in combination with a screw-seat fixed to the fore-end of a gun, as and for the purposes set forth.
- 20 2. A hand-hold for the fore-end of fire-arms, consisting of a rod or bar having an angular

body portion and circular screw-threaded end portions, a nut mounted upon one end of the rod, a sleeve having an angular bore mounted upon the middle portion of the rod, and a metal 25 ferrule mounted on the end portion of the bar opposite to the nut, together with means for attaching the bar to the said fore-end, as shown and described, to operate in the manner set forth, for the purposes stated.

3. A hand-hold for guns, comprising a loop or clasp adapted to encircle a gun-barrel, and a handle adapted to be detachably fixed to the bottom of the loop or clasp and to clamp the clasp fast to the gun in the manner set 35 forth.

FRANK NYE.
RICHARD F. DENHAM.
OLE KNUDSON.
